UNITED STATES PATENT OFFICE

169,477

MUDDLER

Benjamin D. Gilbert, Stamford, Conn.

Application July 31, 1952, Serial No. 20,865

Term of patent 14 years

(Cl. D16—1)

To all whom it may concern:

Be it known that I, Benjamin D. Gilbert, a citizen of the United States, residing at Stamford, State of Connecticut, have invented a new, original, and ornamental Design for a Muddler, of which the following is a specification, reference being had to the accompanying drawing, forming a part hereof, wherein

Fig. 1 is a side elevational view of a muddler, showing my new design;

Fig. 2 is a top plan view thereof; and

Fig. 3 is a bottom plan view thereof.

I claim:
The ornamental design for a muddler, as shown.

BENJAMIN D. GILBERT.
